UNITED STATES PATENT OFFICE

HUGH H. YOUNG, OF BALTIMORE, MARYLAND

SOAP DISPENSER AND SUPPORT THEREFOR

Application filed July 26, 1930. Serial No. 470,953.

The present invention relates generically to dispensing fixtures. More particularly, it has specific relation to pivotally suspended soap dispensing cups and supporting means 5 therefor.

Among the several objects of the present invention are to provide soap dispensers which shall be of extremely simple and efficient construction so that there shall be 10 nothing liable to get out of order or adjustment; which shall be easily and quickly cleaned or sterilized; which shall be easily and quickly filled and operated; which shall be easily attachable to any existing plumbing fixture or to a wall by means of various uncomplicated supports or connections; which shall be substantially unbreakable; which shall be of especial value in hospitals 15 and medical clinics on account of the ease with which they may be kept absolutely sanitary; which shall constitute an aid to aseptic surgical technique; and which shall be capable of manufacture at a very low cost.

To the accomplishment of these objects 20 and such others as may hereinafter appear, the various features of the present invention relate to certain devices, combinations and arrangements of parts fully set forth hereinafter, the advantages of which will be readily understood by those skilled in the art to which this invention pertains.

The various features of this invention will be best understood from a consideration of 25 the following description thereof in the light of the accompanying sheets of drawings, which illustrate several embodiments of the invention.

In the said drawings,

Fig. 1 is a perspective view of one form of 40 dispensing cup and support, shown in connection with one conventional type of plumbing fixture;

Fig. 2 is a sectional view along line 2—2 of Fig. 1, the dispensing cup being removed.

Fig. 3 is a sectional view along line 3—3 of Fig. 1.

Fig. 4 is an elevational showing a second form of dispensing cup, supporting pivot, and a coacting plumbing fixture;

Fig. 5 is an elevation of the hinged cover.

Fig. 6 is a sectional view along line 6—6 of Fig. 4, the dispensing cup being removed.

Fig. 7 is a view similar to Fig. 4, but showing modified forms of dispensing cup, supporting bracket, and plumbing fixture. 55

Fig. 8 is a plan view of the clamping bracket shown in Fig. 7.

Fig. 9 is a view, partly in section and partly in elevation, showing the construction of the end of the clamping bracket. 60

Fig. 10 is a sectional view taken along line 10—10 of Fig. 8.

Referring first to Fig. 1 of the drawings, reference numeral 1 indicates a water-outlet plumbing fixture of conventional type. It is 65 obvious, of course, that any type of fixture of the character illustrated may be utilized. Protruding laterally from the upper part of the said fixture 1 may conveniently be disposed the pivot 2. The said pivot 2 may 70 preferably comprise a main cylindrical body portion (see Fig. 2) and a reduced journal portion 3 at one side of the body portion. Protruding from one end of the body portion may be reduced threaded concentric extension 4. A pin 5 extends radially from the journal 3 adjacent the free end thereof. 75

The pivot 2 may be connected to the fixture 1, as shown in Fig. 2, by threading extension 4 into a coacting threaded opening in the fixture. A washer 6, of any desirable material, 80 may preferably be disposed between the pivot body and the adjacent plumbing fixture 1.

Pendulously supported by the pivot 2 upon its journal portion 3 is a dispensing cup 7. The said cup 7 may be of any convenient or desirable shape, and preferably comprises a cylindrical body 8 closed at each end. The top 9 of the dispensing cup 7 is provided with an unobstructed and valveless outlet spout 10, as illustrated, and a filling opening 11. The said filling opening 11 may conveniently be formed by cutting away a segment of the top 9. 85

Extending from the rear (or inside) of the cup 7 at the top thereof is the perforated lug 12 which forms a sort of ear by which the dispensing cup may be conveniently suspended. The lug or ear 12 is substantially 90 coextensive with the journal 3, which is re- 100

ceived in the journal opening of the former. To securely keep the dispensing cup 7 in place upon its pivot 2, the journal 4 of the latter has radially extending therefrom adjacent its free end, the pin or lug 5. The interior surface of ear 12 is formed with a bayonet slot 13, 14, as clearly shown in Fig. 3, adapted to coact with pin 5. By bringing portion 13 of the bayonet slot into registry 10 with the pin, the cup 7 may be slid onto journal 3. In the normally pendant position of cup 7, pin 5 is lodged in portion 14 of the bayonet slot but out of registry with portion 13, whereby the cup is free to swing about 15 the pivot but is securely kept in place thereon.

As is evident from Fig. 1 of the drawings, the cup 7 may be readily tilted by slight pressure of the hand so that the contents 20 thereof—such as liquid soap—will be freely dispensed from the open outlet or spout 10. Upon removal of the tilting force, the cup 7 will resume its normal position (shown in Fig. 1).

25 The dispensing cup 7 may assume a number of modified forms, such as are shown by way of example in Figs. 4 and 7. The form shown in Fig. 1 has the advantage that the contents of the cup may be easily inspected, 30 and the condition and amount thereof readily noted.

In the modification illustrated in Fig. 4, the opening 11 (of Fig. 1) is covered by the flip cover 15, which is hingedly connected to 35 the top 9, as shown. The ear 12, in this modification, is shaped to coact with a journal portion 3' of relatively reduced width, the remainder of the portion 3' functioning to pivotally receive the eyes 16 of the cover 15. 40 It is obvious that either form of ear may be used with any particular form of dispensing cup 7.

To inspect the contents of the cup 7, in this modification, the closure 15 is merely flipped 45 backwardly about the journal 3', thereby uncovering the filling and inspecting opening 11.

In Fig. 7, the filling opening is circular in form, and may be conveniently closed by 50 closure 17, which may be screw-threadedly connected to the top 9, or a bayonet-slot type of joint may be utilized.

In the modification illustrated in Fig. 4, 55 a second form 1' of conventional plumbing fixture is shown. Extending upwardly from the said fixture, and suitably fastened thereto, is the gibbet-like standard 18 which terminates in the journal portion 3'. The free end of portion 3' is formed with a reduced 60 concentric threaded extension adapted to receive the knurled nut 19 to securely hold the cup 7 swingably in place.

In Fig. 7, a further modification of pivot, connector, and plumbing fixture is shown. 65 The latter comprises the vertically extending

water outlet 20. The connector comprises the two-part clamp 21 connected by bolts, screws or the like 22, and adapted to embrace a plumbing fixture, such as fixture 20. The reduced body portion of the clamp has securely fixed thereto, as by sweat soldering, a sleeve 23 which culminates in a still further reduced journal 3".

70 Means are provided to securely keep cup 7 operatively in place upon the journal. As shown in Figs. 7, 8 and 9, this means may take the form of a button-shaped head 24 of a width slightly less than the width of the journal 3", so that the cup 7 may be slipped thereover and onto the journal. Normally the 75 head assumes the position shown in Fig. 9, preventing the ear 12 which may be journaled on the portion 3" from moving off therefrom. The journal portion 3" is slotted as at 25. Extending inwardly from the head 24 and 80 through the slot 25 is the spring rod 26. The innermost end of the latter is suitably secured to the body of the clamp 21. Because of the 85 springy character of the rod 26, the head 24 is yieldably held in place adjacent the free 90 end of journal 3".

95 While I have illustrated and described several particular embodiments of my invention, it will be understood that these are merely exemplary and that various structural modifications may be made therein without departing from the spirit and scope of the invention as set forth in the appended claims.

I claim as my invention:

1. In a dispensing device including a journal and a receptacle swingably supported thereon, means on said journal holding said receptacle against relative longitudinal movement with respect to the journal except in a predetermined position of said device, while permitting unlimited relative rotary movement.

100 2. The combination set forth in claim 1, said means comprising a pin extending radially from said journal and a bayonet slot in 110 the interior surface of said ear.

HUGH H. YOUNG.
